DESIGN FOR A CASING FOR A JUICE EXTRACTOR OR THE LIKE

Albert D. Grau, Tacoma, Wash.

Application October 21, 1940, Serial No. 95,969

Term of patent 14 years

To all whom it may concern:

Be it known that I, Albert D. Grau, a citizen of the United States of America, residing at Tacoma, county of Pierce, State of Washington, have invented a new, original, and ornamental Design for a Casing, for a Juice Extractor or the like, of which the following is a specification, reference being had to the accompanying drawing, forming a part thereof, wherein:

Figure 1 is a perspective view of a casing, for a juice extractor or the like, showing my new design.

I claim:

The ornamental design for a casing, for a juice extractor or the like, as shown.

ALBERT D. GRAU.
